UNITED STATES PATENT OFFICE.

HAROLD D. BOWIE, OF MAHWAH, NEW JERSEY, ASSIGNOR TO E. I. HORSMAN & AETNA DOLL CO., OF NEW YORK, N. Y., A CORPORATION OF NEW YORK.

DOLL.

Application filed November 19, 1921. Serial No. 516,323.

To all whom it may concern:

Be it known that I, HAROLD D. BOWIE, a citizen of the United States, and resident of Mahwah, county of Bergen, State of New Jersey, have invented certain new and useful Improvements in Dolls, of which the following is a specification.

My invention relates to toy figures and more particularly to dolls and the like and 10 has for its object to provide a doll or other figure constructed in a novel and simplified manner to automatically simulate the motion of walking. A further object of the invention is to construct the legs of the 15 doll and the means whereby a walking motion is imparted thereto in the form of a unit capable of being readily and efficiently combined with the body of the doll and detached therefrom as a whole whenever, for 20 any reason, this is desired. My invention further contemplates the provision of an 25 arm and body construction adapted for co-operation with the walking means in a manner to increase the efficiency of the figure in its particular class. Other objects of the invention will appear from the description hereinafter and the features of novelty will be pointed out in the appended claims.

30 In the accompanying drawings, which illustrate an example of the invention without defining its limits, Figure 1 is an elevation of a doll embodying my improved construction and with parts broken away; Fig. 35 2 is a longitudinal section thereof on the line 2-2 of Fig. 1; Fig. 3 is a cross-section on the line 3-3 of Fig. 1; Fig. 4 is a detail view of the unit consisting of the legs and walking means of the figure; Fig. 5 is a sectional view thereof on the line 5-5 of Fig. 40 4, and Fig. 6 is a horizontal section on the line 6-6 of Fig. 4.

45 In the illustrated example which, for the purposes of description, discloses the invention applied to a doll, 10 represents the body, which may be constructed of any suitable material in the customary hollow form and at its upper end is provided in the well known way with a recess 11 in which the 50 neck 12 is seated in a manner to render the head 13 capable of being adjusted to different positions. The means whereby the neck and head are fixed in connection with the body 10 will be referred to hereinafter.

55 The unit consisting of the legs and the

means whereby a walking motion is applied thereto, and which constitutes an essential element of the present construction, comprises a supporting member 14 of a size and shape to approximately fit within the body 60 10 near its lower end. Side members 15 depend from the member 14 at diametrically opposite points and carry a rod 16 which is fixed therein and bridges the space between said side members 15, as shown in Fig. 4. 65 The legs 17 are pivotally mounted upon the rod 16 and are preferably provided on the outside with bearing recesses 18 into which the side members 15 extend and which co-operate therewith to stabilize the construction 70 against wobbling. On the inside each leg 17 carries a lug 19 which projects upwardly therefrom and is pivotally connected at 20, in any suitable manner, with the opposite and spaced runs *a* and *b* of an endless 75 belt 21; the latter may be of any suitable type so long as it is substantially inelastic and, as shown, may be constructed of webbing or fabric, although it is to be understood that any other flexible material of relatively low inherent elasticity may be employed. The endless belt 21 or its equivalent 80 is movably mounted beneath the supporting member 14 in such a manner that its runs *a* and *b* are reciprocable forwardly and rearwardly with respect to the direction of travel of the figure. In the preferred construction the belt 21 or its equivalent is mounted in such a manner or is itself so constructed that the runs *a* and *b* are incapable of any material movement toward 85 each other and thus serve, in co-operation with the lugs 19, to maintain the legs 17 in the intended positions and properly separated on the rod 16. The illustrated example shows the belt 21 mounted upon a bearing means in the form of a rigid rib 22 which depends from the supporting member 90 14 and extends transversely across the same in a forward and rearward direction; the 100 rib 22 has its opposite ends rounded to facilitate the operation of the belt 21 and lies between the runs *a* and *b* thereof and forms a backing therefor whereby said runs 105 are prevented from being pressed toward each other.

When the leg unit is operatively combined with the figure the supporting member 14 is located within the body 10 at a distance 110 from the lower end thereof and rests against

abutments 23 formed at the proper points within said body, as shown in Fig. 1. A preferably elastic connection 24 extends between the supporting member 14 and the neck 12 and serves to hold the latter and its head 13 in proper position upon the body 10 and at the same time maintains the supporting member 14 in position against the abutments 23; it will be understood that the parts are located and proportioned in such a manner that the connection 24 will be under tension. This connection, in addition to its other functions, permits the head and neck to be adjusted to different life-like positions on the body and because of the fact that it is under a tension fixes the same in such positions. As an additional means for maintaining the leg unit in proper combination with the body, a filler piece 25 may be fitted between the legs 17 and secured in place by means of nails or other removable fastening devices 27; the filler piece 25 is recessed at 28 to receive the rod 16 and to bear against the same and thereby assist to fix the leg unit against unintentional displacement. The filler piece 25 furthermore is shaped to carry out the contour of the body and thus serves also to complete the appearance of the figure.

The illustrated example of the invention further includes arms 29 which are movably connected with the body 10 in a novel manner to efficiently co-operate with the walking mechanism. As shown, the body 10 is provided at the proper places with arm recesses or openings 30, the general circular form of which is interrupted by lugs 31 shaped to correspond to quadrants of said circular recesses; that is, the free edges *c* and *d* of said lugs 31 extend in radial directions approximately at right angles to each other. The arms 29, in turn, are provided with inwardly extending projections 32 located in the recesses 30 and having bearing surfaces *e* curved approximately in conformity with and bearing upon the curved peripheries thereof; in addition, the projections 32 are formed with flat surfaces *f* extending diametrically to the axes of rotation of said arms, and adapted by engagement with the surfaces *c* and *d* of the lugs 31 to arrest the pivotal movements of the arms 29. A connection 33, preferably including a turn-buckle or equivalent 34, extends between the projections 32 within the body 10 and serves to maintain the arms 29 in proper connection therewith; by adjusting the connection 33 through the medium of the turn-buckle 34 or its equivalent, the arms 29 may at all times be properly positioned in the recesses 30.

To cause the figure, in the present instance a doll, to walk, one or the other of the arms 29 is grasped with the hand and moved to a position corresponding approximately

to the position assumed by the arm of a child when being led by another person; in this condition of the parts the flat surface *f* of the arm in question will lie against the surface *c* of the co-operating lug 31 and accordingly will fix said arm against any further movement in an upward direction relatively to the body 10. In other words, at this stage, said arm and body comprise a temporarily rigid unit capable of being manipulated through the medium of said arm 29.

After the parts have been positioned as described, the arm 29 is manipulated to support the body 10 upon one of the legs 17, after which said arm is moved in an upward direction to cause the body 10 to swing toward the rear; the supporting member 14 and side members 15 partake of this rearward swinging movement of the body which, as a matter of fact, has the rod 16 and its bearing in that leg upon which the body is temporarily supported, as a centre or pivot. Because of the fact that during this operation the supporting leg remains stationary, a pull will be exerted by the lug 19 of said leg upon the run *a* of the belt 21. This pull will be in a direction to cause said run *a* to move in a forward direction and consequently will move the run *b* of said belt toward the rear; this rearward movement of said run *b* will be communicated to the lug 19 of the other leg 17 and, as a result, will pivotally swing said other leg on the rod 16 toward the front so as to bring its foot to a position in advance of the foot of the leg upon which the body is resting. The doll is now swung forwardly upon the supporting leg, the foot of which rocks upon the surface upon which the doll is positioned; this movement is continued until the second leg comes into contact with said surface in an upright position and thus becomes the supporting leg. The point at which this takes place is in advance of the point occupied by the first leg as a supporting member, so that the doll has walked one step; at this stage the first leg extends rearwardly in a position inclined downwardly from the rod 16. If the body is now again rocked by means of the arm 29 in the manner previously described, the run *b* of the belt 21 will be pulled in a forward direction and accordingly will pull the run *a* rearwardly and consequently swing the first leg to a forwardly-inclined position in advance of the second leg which, during this operation, is the supporting leg. By again swinging the doll forwardly upon this supporting leg in the manner previously described, the first leg is again brought into engagement with the surface upon which the doll is traveling at a point in advance of that at which the second leg came to rest, so that the doll has advanced another step.

This alternate operation of the legs through the medium of the belt 21 causes the doll to walk in a life-like and efficient manner and is accomplished without effort by means of one or both arms 29; the described walking of the doll is facilitated because of the fact that the manipulating arm is rigidly connected with the body by the co-operative action of the surfaces *c* and *f* and thus temporarily becomes fixed with respect to the body 10 in a position corresponding to the natural position of the arm of a child being led by the hand.

During the walking operation the endless belt 21 is reciprocated upon the rigid rib 22 and positively actuates each leg alternately in a smooth, even manner free from jerkiness and so as to accurately imitate the natural act of walking.

20 The leg unit, including the walking mechanism, may be readily detached from the body 10 when required, by simply removing the fastening devices 27 and filler piece 25 and disconnecting the connection from the neck 24, which may be readily accomplished by withdrawing the neck 12 from the recess 11 against the elasticity of the said connection until the point of attachment of the latter with said neck is accessible.

30 The arrangement is simple and efficient in operation and is capable of being easily and quickly repaired and adjusted whenever this may be required.

Various modifications in the specific form shown and described may be made within the scope of the claims without departing from the spirit of my invention.

I claim:

1. A travelling figure comprising a body, legs movably connected with said body, a continuous substantially non-elastic member having runs spaced apart and each connected with one of said legs, and bearing means whereby said runs are maintained in spaced relation and upon which said continuous member is movable to reciprocate its runs forwardly and rearwardly with respect to the direction of travel of said figure whereby said legs are alternately actuated to advance said figure in walking steps.

2. A travelling figure comprising a body, legs pivotally connected therewith, bearing means carried by said body and an endless substantially non-elastic belt mounted upon said bearing means to provide spaced runs and having said runs connected with said legs and reciprocable on said bearing means in forward and rearward directions with respect to the direction of travel of said figure whereby said legs are alternately actuated to advance said figure in walking steps.

3. A travelling doll comprising a hollow body, a combined neck and head mounted thereon, abutments within said body, a sup-

porting member within said body in engagement with said abutments, a connection between said neck and supporting member whereby both are secured upon said body, legs pivotally mounted upon said supporting member, bearing means thereon and an endless, substantially non-elastic belt mounted on said bearing means to provide spaced runs and having said runs connected respectively with said legs and reciprocable in forward and rearward directions to alternately actuate said legs in a manner to advance said doll in walking steps.

4. A travelling doll comprising a hollow body, a combined neck and head mounted thereon, abutments within said body, a supporting member within said body in engagement with said abutments, a connection between said neck and supporting member whereby both are secured upon said body, legs pivotally mounted upon said bearing member, bearing means thereon, an endless, substantially non-elastic belt mounted on said bearing means to provide spaced runs and having said runs connected respectively with said legs and arms connected with said body and adapted to actuate the latter upon one of said legs to cause a pull to be exerted upon said endless belt whereby the other leg is pivotally advanced in a walking movement.

5. A travelling doll comprising a body having arm openings, legs movably connected with said body, walking mechanism operatively connected with said legs, arms, projections on said arms extending inwardly into said arm openings and constituting bearings for the pivotal movements of said arms and lugs projecting from the peripheries of said arm openings toward the centre thereof into the path of said projections, whereby the pivotal movements of the arms in one direction are arrested to fix said arms in positions for manipulating said body to operate said walking mechanism and legs.

6. A walking doll comprising a body having circular arm recesses, projections in said recesses having radially extending surfaces, arms, projections on said arms extending into said recesses and having bearing surfaces in engagement with the peripheral surfaces thereof for pivotally mounting the arms in opposite directions therein to move about axes transverse to the walking direction, said projections having flat surfaces extending diametrically to the axes of rotation and arranged to abut against the radial surfaces of said projections to arrest the pivotal movements of said arms, legs movably connected with said body and walking mechanism adapted to impart a progressive walking movement to said legs.

7. In a walking doll, a unit comprising a supporting member adapted to fit within the body of the doll in transverse relation to

the direction of walking, legs pivotally mounted on said member and depending therefrom and an endless member movably mounted on said supporting member to provide spaced runs extending in directions parallel with the direction of walking and having said runs connected respectively with said legs for imparting a walking movement thereto.

10 8. In a walking doll, a unit comprising a supporting member adapted to fit within the body of the doll in transverse relation to the direction of walking, legs pivotally mounted on said member, a rigid rib depending from said supporting member and extending across the same in a direction parallel with the direction of walking and an endless belt movably mounted upon said rib to provide spaced runs and having said runs connected respectively with said legs for imparting a walking movement thereto.

9. A travelling doll comprising a hollow body having a recess, a combined neck and head mounted in said recess, abutments within said body, a supporting member within said body in engagement with said abutments, an elastic connection between said neck and supporting member whereby said neck and head are resiliently held in said recess and said member is held against said abutments, legs pivotally mounted upon said bearing member, bearing means thereon and an endless substantially non-elastic belt mounted on said bearing means to provide spaced runs and having said runs connected respectively with said legs and reciprocable in forward and rearward directions to alternately actuate said legs in a manner to advance said doll in walking steps.

In testimony whereof I have hereunto set my hand.

HAROLD D. BOWIE.
